UNITED STATES PATENT OFFICE.

JOSEPH LAURENCE DICKELMAN, OF FOREST, OHIO.

DESIGN FOR A SHINGLE.

No. 38,931.

Specification for Design.

Patented Dec. 3, 1907.

Application filed September 27, 1907. Serial No. 394,930. Term of patent 14 years.

To all whom it may concern:

Be it known that I, JOSEPH LAURENCE DICKELMAN, a citizen of the United States, residing at Forest, in the county of Hardin and State of Ohio, have invented a new, original, and ornamental Design for Shingles, of which the following is a specification, reference being had to the accompanying drawing, forming part thereof.

The figure is a perspective view of a shingle showing my new design.

I claim:

The ornamental design for a shingle, as shown.

JOSEPH LAURENCE DICKELMAN.
